T. H. GARLAND,
WINDOW VENTILATOR,
APPLICATION FILED JULY 6, 1908.

904,125.

Patented Nov. 17, 1908.

UNITED STATES PATENT OFFICE.

THOMAS H. GARLAND, OF CHICAGO, ILLINOIS.

WINDOW-VENTILATOR.

No. 904,125.

Specification of Letters Patent. Patented Nov. 17, 1908.

Application filed July 6, 1908. Serial No. 442,079.

To all whom it may concern:

Be it known that I, THOMAS H. GARLAND, a citizen of the United States, residing at Chicago, in the county of Cook and State of Illinois, have invented certain new and useful Improvements in Window - Ventilators, of which the following is a specification.

This invention relates to improvements in window ventilators, and refers more particularly to a window ventilator in which the passage of external currents through the ventilator in either direction produces an eductive action which withdraws air from the compartment being ventilated; the construction and arrangement being such that the inducing drafts do not enter the compartment.

Among the salient objects of the invention are to provide a device by which a room or apartment may be effectively ventilated by withdrawing the vitiated or foul air without admitting into the room external air through the ventilator; to provide a construction which is extremely simple and of low cost, and which can be adjusted either within the upper or lower part of the window and without in any wise mechanically changing the window construction; to provide an efficient device devoid of moving parts; to provide a construction in which a comparatively slight external draft will induce an effective exhausting or eductive action through the ventilator; to provide a construction which is well designed to prevent the entrance of rain, snow, sleet, etc.; and in general to provide an improved device of the character referred to.

To the above ends the invention consists in the matters hereinafter described, and more particularly pointed out in the appended claims.

The invention will be readily understood from the following description, reference being had to the accompanying drawing, in which—

Figure 1 is a perspective view of the upper portion of a window equipped with my improved ventilator; Fig. 2 is a horizontal sectional view through the central part of the ventilator; Fig. 3 is a cross sectional view through the ventilator in edge elevation.

In the preferred construction illustrated, the ventilator proper comprises a base plate

posed slot-like opening 2, upper and lower plates 3 and 4, respectively, a convex outer side wall, to which the outer edges of the upper and lower plates 3 and 4 conform and certain internal deflectors. The ends of the 60 ventilator are open.

Describing the deflectors: Coincident with the side margins of the eduction opening 2 are arranged deflectors 6, 6, consisting of plates which extend from top to bottom of 65 the ventilator and from the base plate of the latter laterally a distance preferably somewhat less than half the horizontal width of the end openings. Within each end of the ventilator is arranged another deflector, or 70 partition plate, as 7, extending from top to bottom of the device and so arranged as to sub-divide the open ends of the ventilator; said deflectors being to this end preferably arranged to extend as to their main portions 75 parallel with, or approximately parallel with, the base plate. The inner ends 8 of these deflectors are bent at right angles outwardly, or towards the convex side of the ventilator, so as to constitute deflector portions 80 which direct the currents of air entering the outer half of each end of the ventilator towards the convex or outer side of the latter. The deflectors 7 preferably extend from points coincident with the end 85 margins of the ventilator inwardly to points approximately half, or a little more than half, the distance between the end of the ventilator and the corresponding deflector 6, so that passages 9 are formed between the 90 edges of the deflectors 6 and the deflectors 7. Thus arranged the deflectors 6 act to deflect the currents of air entering the inner halves of the ventilator outwardly toward the convex side of the ventilator in substantially the 95 same manner as do the deflectors 7, as before described. The result of this arrangement is that the air entering either end of the ventilator is divided into two currents by the straight or parallel portions of the deflectors 100 7, and both of the two currents deflect outwardly in such way as to create swirls or eddies in that portion of the ventilator within and immediately opposite the eduction opening 2; the air passing on out through 105 the opposite end of the ventilator in an obvious manner. This abrupt outward deflection of the two volumes of air produces a pronounced induction effect through the outlet opening 2, due both to the molecular 110

friction or aspirating effect and to the rarefaction incident to the flow of the currents of air in outwardly curved paths around the inner edges of the deflectors 6 which define 5 the eduction opening and the parts 8 which deflect the outer current.

I have found in practice that the device thus constructed is extremely effective and produces an ample ventilation, even when 10 there is but a slight breeze or movement of the external air.

The ventilator is most advantageously mounted in proper relation in the window by mounting it upon a board or strip 10 of uniform width and cut to the proper length 15 to occupy the full width of the window; the sash being simply lowered or raised, as the case may be, the ventilator board inserted and the sash closed upon it so as to hold it 20 in position. The base board 10 is, of course, provided with an opening 2' in register with and the same size as the opening 2 in the bottom of the ventilator proper. The board 10 may be of the same vertical width as the 25 ventilator, or somewhat wider if preferred.

It will be understood from the foregoing description that the device fully accomplishes each of the several objects hereinbefore stated, and operates in accordance with 30 the approved modern practice of ventilating compartments, cars, etc., by withdrawing the vitiated or foul air as distinguished from those devices which undertake to inject air from the outside.

35 The two longitudinal halves of the ventilator are symmetrically constructed and arranged so that in which ever direction the current of air passes through the ventilator the eduction effect is the same.

40 Of course the ventilator need not be applied to a window to be effective, but may be placed anywhere upon the outside wall of the compartment over any opening in the wall communicating with the interior there- 45 of and may even be located at a distance from the wall if provided with a duct or conduit which communicates with the interior of the room.

While a ventilator having but a single air 50 passage and provided with but a single set of deflectors which produced the current flow and eddying effects opposite the eduction opening would be operative to some degree in educting air from the room, nevertheless 55 the second or outer passage, by reason of the swirling motion of the air in that passage is cumulative, in effect, to the swirling motion in the first passage, by increasing the 60 tendency to produce a vacuum opposite the eduction opening in the base plate and thus increase the efficiency of the device. The claims are therefore drawn to cover not only the plural passage form shown, but the device when organized with but a single pas- 65 sage.

I claim as my invention:

1. A ventilator comprising a casing open at both ends, provided at its base side intermediate its length with an eduction opening, deflectors parts arranged within the respective ends of said casing to longitudinally divide the inlets thereof and other deflector parts extending from, and at abrupt angles to, said first deflector parts and towards the side of the casing remote from the base side, 70 whereby the air currents passing through the deflector are deflected abruptly away from the said eduction opening and eddying currents produced opposite the latter. 75

2. A ventilator comprising an open-ended 80 casing having a substantially flat base side and provided in its said base side with an eduction opening, deflectors extending from the base inwardly at each side of said opening and forming an eduction passage debouching in the central interior of the device, other deflectors arranged in the respective ends of the ventilator to longitudinally divide the inlet portions thereof, said latter deflectors being provided at their inner ends 85 with angular portions arranged to deflect the air passing therethrough in the same direction as do the deflectors which form said eduction passage. 90

3. A ventilator comprising an open-ended 95 casing having a substantially flat base side and a convex side opposed to said base and provided in its said base side with an eduction opening located approximately mid-length thereof, deflectors extending from the 100 base inwardly at each side of said opening and forming an eduction passage debouching in the central interior of the device, an L-shaped deflector arranged in each end of the ventilator, one part of the deflector being 105 arranged to longitudinally divide the inlet of the ventilator and the other portion of the deflector being arranged to extend towards the convex side of the ventilator, and means for mounting said ventilator in 110 a window opening. 115

4. A ventilator comprising an open-ended casing having a substantially flat base side, a convex side opposed to said base side and substantially flat top and bottom sides, said 120 base side being provided with an eduction opening located midlength thereof, deflectors extending from the base inwardly at each side of said opening and forming an eduction passage debouching in the central 125 part of the device and substantially at right angles to the length of the latter, other deflectors arranged one in each of the respective ends of the ventilator to longitudinally divide the inlet portions thereof, each of the latter deflectors being provided with an angular extension arranged to extend transversely and towards the convex side of the device, and a window board or plate to which the base side of the ventilator is se- 130

cured, provided with an opening corresponding to and registering with the eduction opening in the base of the ventilator.

5. In a ventilator, an open-ended casing provided in its base side with an eduction opening, communicating with the interior of the room to be ventilated, and having a plurality of longitudinal air passages, each passage being provided with deflector plates arranged to extend from the base wall of such

passage transversely and outwardly therefrom, the several passages being provided in their base walls with openings which are opposite or in register with each other and with the eduction opening or openings in the 15 base side of the casing.
